UNITED STATES PATENT OFFICE

148,316

DESIGN FOR A CABINET FOR AUTOMATIC PHONOGRAFPHS

Nels A. Miller, Oak Park, Ill., assignor to J. P. Seeburg Corporation, Chicago, Ill., a corporation of Illinois

Application May 4, 1946, Serial No. 129,325

Term of patent 14 years

(Cl. D56—4)

To all whom it may concern:

Be it known that I, Nels A. Miller, citizen of the United States, and resident of Oak Park, in the county of Cook and State of Illinois, have invented a new, original, and ornamental Design for Cabinet for Automatic Phonographs, of which the following is a specification, reference being had to the accompanying drawings, forming part thereof.

Figure 1 is a perspective view of a cabinet for automatic phonographs showing my new design;

Fig. 2 is a plan view of the cabinet; and
Fig. 3 is a side elevation of the cabinet.

I claim:

The ornamental design for a cabinet for automatic phonographs, as shown.

NELS A. MILLER.
